UNITED STATES PATENT OFFICE

OSCAR ZINGG, OF BADEN, SWITZERLAND, ASSIGNOR TO AKTIENGESELLSCHAFT BROWN BOVERI & CIE., OF BADEN, SWITZERLAND, A JOINT-STOCK COMPANY, OF SWITZERLAND

HEATING DEVICE

Application filed August 25, 1926, Serial No. 131,335, and in Germany September 17, 1925.

This invention relates to construction of electric heating units for the heating of air or other gaseous fluids wherein the fluid is passed over a heating coil or spiral in the 5 direction of the longitudinal axis of the latter.

The general object of the invention is to increase the efficiency of such devices by more effective utilization of the entire heating 10 surface of the coil.

Another object is the provision of a construction whereby the heating effect of the entire coil may be utilized to best advantage without the necessity for a plurality of inlet 15 ports for the fluid to be heated.

Other and further objects will be pointed out or indicated hereinafter or will occur to one skilled in the art upon an understanding of the invention or its employment in 20 practice.

In the drawing forming a part of this specification, I illustrate various arrangements wherein the invention may be embodied, but these are presented for purpose of illustration only and the claims are not to be regarded as limited simply to these.

In said drawing,

Fig. 1 is a longitudinal sectional view of a tubular heating device containing an electrically heated coil;

Fig. 2 is a cross sectional view of same, the section being taken on the line 2—2 in Fig. 1;

Fig. 3 is a view similar to Fig. 1, showing a modified form of heating element; and

Fig. 4 is a view similar to Fig. 1, showing a further modified form.

When an electric heating spiral is subjected to a stream of air directed chiefly along its longitudinal axis, it usually occurs that 40 the temperature of the spiral at the end where the cooled air enters will run lower than at the end where the heated air leaves. This results in a rather inefficient employment of the heating energy and gives rise to 45 other undesired results. The present invention provides a construction whereby the movement of the air is accelerated as it passes along the spiral in such fashion that the velocity of the air relative to the individual 50 turns of the spiral increases as it approaches

the outlet end. With this effect, the heating efficiency of the spiral throughout its entire length is availed of to better advantage and overheating at the exit end is avoided.

In Fig. 1 is illustrated a heating device 55 comprising a refractory tubular member 10 having a conical bore or tunnel of diameter d at the inlet end and diameter d' at the outlet end, and reference numeral 11 designates a connection whereby air is supplied 60 to the tunnel at the inlet end. Within the tunnel of the tubular member are provided narrow radially extending ribs 12 tapering in height from the inlet to the outlet end 65 so that their crests lie upon substantially the same radius from the axis of the tubular member, throughout their length. Upon these ribs is mounted the spiral 14 of resistance wire, which is arranged for connection at its ends to an appropriate source of 70 electric current. Air supplied to the inlet end of the tubular member, from the connection 11, at a suitable pressure, passes longitudinally through the tunnel of the former about and in contact with the heating spiral 75 14. Due to the tapering form of the tunnel, and also to the expansion of the air as it becomes heated, the rate of flow of the air increases as it passes through the tunnel, with the result that the turns of the 80 spiral at the outlet end are subjected to a much more rapid flow than those at the inlet end. Consequently, there is a more nearly uniform transfer of heat from the spiral to the air throughout the entire length 85 of the former than is the case when the only acceleration of the air is that resulting from its expansion by the heat.

Fig. 3 shows a modified form in which the turns of the spiral 14' are supported 90 directly on the walls of the conical bore of the tubular member 10'. In this arrangement the spiral is of tapering form so that a greater amount of heating surface is exposed by the turns adjacent the inlet end 95 than those at the outlet end, the amount of heat transfer surface exposed per unit of length of the tubular member gradually decreasing from inlet to outlet. The tapering form of the tunnel in this embodiment con- 100

tributes to the acceleration of the flow of air through the element, as in the form first described.

In the embodiment illustrated in Fig. 4
5 the tubular member 10 is of the form illustrated in Fig. 1, but the heating spiral 14", while of uniform diameter from end to end, has the pitch of the turns gradually increased from the inlet end to the outlet end. This,
10 accordingly, disposes more heating surface in the larger portion of the tunnel where the cold air enters, than in the portions farther toward the outlet, and in conjunction with the accelerating effect of the conical tunnel,
15 contributes to the rapid heating of the air and uniform extraction of heat from the spiral throughout its length.

Thus the invention contributes to efficiency by increase of output of the heated fluid,
20 more uniform use of the heating surface and avoidance of overheating of the element in any part.

What I claim is:

In a heating device of the character described, a casing member having a passage extending from end-to-end thereof, the cross-sectional area of such passage decreasing at a substantially uniform rate from one end of said casing member to the other end thereof,
30 and a heating element disposed in such passage and being directly engaged and supported by the material forming the interior surface portion of said casing member.

In testimony whereof I have hereunto subscribed my name at Zurich, Switzerland, this
35 9 day of August, A. D. 1926.

OSCAR ZINGG.
